UNITED STATES PATENT OFFICE.

BENJAMIN F. HEUER, OF STURGIS, SOUTH DAKOTA.

METALLIC VESSEL.

1,263,765.

Specification of Letters Patent. Patented Apr. 23, 1918.

Application filed July 31, 1916. Serial No. 112,351.

To all whom it may concern:

Be it known that I, BENJAMIN F. HEUER, a citizen of the United States, residing at Sturgis, in the county of Meade and State of 5 South Dakota, have invented certain new and useful Improvements in Metallic Vessels; and I do hereby declare the following to be a full, clear, and exact description of the invention, such as will enable others 10 skilled in the art to which it appertains to make and use the same.

This invention relates to an improved construction of metal receptacles particularly pails, tubs, wash boilers and the like.

15 The object of my invention is to provide an improved form of pail construction which will increase the life of buckets, and similar receptacles, without adding to their cost. In order to insure the proper strength 20 and endurance to pails and similar receptacles, it is necessary to provide them with reinforced flanges around their lower edges, this being particularly true in connection with milk pails, wash boilers and tubs which 25 are constructed from comparatively heavy sheet metal. Furthermore it is also necessary to construct the vertical seams and joints, other than the joints between the bottom and sides of crimped or folded type, in 30 order to insure the proper life of the vessel.

In the present practice, as known to me, these reinforcements are provided by flanges which are stamped from the metal which forms the body of the vessel, and the seams 35 are formed around the bottom and the side of the vessel by crimping and soldering the edges of the metal. This method requires the use of machinery of expensive construction. My improved construction contem- 40 plates the use of soldered seams, either of the lapped or butted type and overlying reinforcing plates of comparatively light wrought metal strips, the latter also being welded or soldered in place. This construc- 45 tion provides a very strong vessel, one which does not need the formation of bottom flanges for reinforcing purposes or to act as feet, since in reinforcing the bottom corners of the vessel angularly bent strips are used 50 to lap the walls and bottom of the vessel, the horizontally projecting portion of the angularly bent strip then serving as a foot, as well as a strengthening device. With the 55 above object in view my invention will now be fully set forth and described, reference being had to the accompanying drawings.

Figure 1 is an elevation of a pail showing one embodiment of the invention.

Fig. 2 is a section on line 2—2 of Fig. 1.

Fig. 3 is a section on line 3—3 of Fig. 1. 60

In the drawings I have elected to disclose the invention as employed in the construction of a pail, this embodiment clearly disclosing the features of the construction which may be used in connection with the 65 manufacture of the metallic receptacles of the household type which might come within the same category.

Referring now to said drawings, 1 denotes the body of the pail and 2 the bottom thereof. In the present instance, the vertical edges of the body portion are lapped and soldered as shown in Fig. 2. The bottom 2 is cut to fit within the lower edge of the body 1, so that its marginal or peripheral edge abuts against the interior surface of the body. The parts are soldered or welded in this relation, and are then covered upon their outer faces with the single strip 3, which closely overlies the joint *a* between the body 1 and the bottom 2 and extends upwardly along the side of the body. Covering the lap *b* which joins the vertical edges of the body 1 is a strip 4 which is preferably shaped to the curvature of the 85 body 1 and is welded or soldered throughout its width to the body and the joint *b*. A corresponding strip 4' reinforces the diametrically opposite side of the pail. The strips 4 are connected to the angle strip 3 90 by the dove-tailed joints 5, on the bottoms of the strips 4, the latter being cut off above the bottom 2 of the pail and being shaped into the dove tail 5 which is set into the correspondingly formed recess 6 formed in the 95 upper edge of the vertical portion of the angle strip 3. The dove tailed-heads 5 thus lie flush with the strip 3. By locking the strip 4 to the angle corner strip 3, the construction is not only greatly strengthened, 100 but the reinforcing or covering elements are provided with a neat finish which adds the necessary completeness to the finished article.

The upper ends of the vertical strips 4 105 terminate in the out-turned integral eyes or loops 7, which provide a means for attaching the handle 8 to the pail. Thus, the vertical reinforcing strips 4 and the angle strips 3 to which the vertical elements are locked 110 practically provide a support for the pail body, whereas in those constructions in

which the pails or other vessels are provided with handles riveted or otherwise secured directly to the pail body, the metal is weakened at the very points where they should be the strongest, namely, at the places where the greatest strain comes when the filled vessels are lifted by the handles.

From the foregoing it will be evident that I have conceived a construction for metallic vessels which is at once extremely simple and free from the ordinary complication of folded or crimped seams and joints which make up the constructions which are at present generally accepted. Furthermore, my improvement results in a stronger vessel, since it practically incloses the body of the vessel in a framework which relieves the body from carrying strains as well as relieving the bottom joint of all knocks and jars and the body of a large number of the blows which result in the disfigurement of the vessel. Should the occasion arise, it is even possible to renew the bottoms of pails constructed according to this invention without undue labor or expense, the bottom angle

strip permitting the close fitting into position and soldering of a new bottom section.

What I claim as my invention is:—

A metallic receptacle comprising in combination a body having vertical seams joining the ends of the body blank, a bottom having its marginal edge butted against the lower edge of the body blank, an angle strip inclosing the joint between the bottom and body blank, said strip having dove-tailed recesses formed in its upper edge upon opposite sides, vertical strips covering the seams in the body, dove-tailed locking joints on the lower ends of said vertical strips and fitting into the recesses in said angle strips, and handle loops formed on the upper ends of the said vertical strips, said angle strip holding the bottom against the lower edge of the body.

In testimony whereof, I affix my signature, in the presence of two witnesses.

BENJAMIN F. HEUER.
